INDICATING DEVICE FOR PAPER-CUTTING MACHINES.

1,402,543.

Specification of Letters Patent. Patented Jan. 3, 1922.

Application filed August 6, 1920. Serial No. 401,701.

To all whom it may concern:

Be it known that I, FRANK O. SCOTT, a citizen of the United States, and a resident of Mittineague, in the county of Hampden and State of Massachusetts, have invented 5 certain new and useful Improvements in Indicating Devices for Paper-Cutting Machines, of which the following is a specification.

10 This invention relates to improvements in indicating devices for paper cutting machines, and more particularly to a device for indicating or determining the position of certain visible markings, such as water- 15 marks, recurring at intervals in the continuous web of paper, whereby the cutting operation may be regulated to insure the locating of such marks at a predetermined point in the separate sheets cut from the 20 web.

In the operation of cutting paper into sheets of the required size it is desirable that the water-mark be disposed uniformly with respect to the margins thereof, as for 25 instance, at the center of each sheet, this being particularly desirable in the better grades of paper to be used for letter-heads and correspondence stationery. To accomplish this end the maintenance of a uniform 30 relation between the feeding of the web of paper and the action of the cutter element is essential in order that the cutting will take place at predetermined intervals with respect to the location of the recurring 35 marks in said web. In practice, however, it has been found difficult to accurately synchronize the feeding and cutting operations in the ordinary cutting machine, so that the desired relationship will be constantly maintained. 40 In the usual type of paper cutting machine the paper is fed at a uniform rate of speed, and the speed of the cutter element regulated to cut at intervals determined by the size of sheet desired, the latter being 45 driven through the medium of speed regulating devices under the control of the operator, which may also be used for rectifying any slight irregularities in the feeding or cutting of the paper. In spite of the efforts 50 of the operator, great difficulty has been experienced in controlling the cutting operation, so as to overcome a common tendency for the paper to creep, that is to say, to feed irregularly so that a designated point in one

sheet, as for instance a water-mark, will 55 occur at a slightly advanced position in the succeeding sheet, and so on, gradually approaching the edge of the sheet until the line of cutting passes through the mark, and parts thereof occurring on two separate 60 sheets. It is possible, however, to overcome the tendency just recited by manipulation of the speed regulating mechanism, providing some means is employed to guide the operator in making the required adjustment, that is, an indicator which will accurately locate the proper position where the mark should reoccur in the web, this enabling the operator to determine exactly 70 the nature and degree of adjustment required from time to time, in order to insure the predetermined location of the watermark in each sheet.

The purpose of the present invention, therefore, to provide a novel construction 75 for an indicating mechanism designed to fulfil the functions above outlined, and a preferred embodiment of the device as applied to a cutting machine of otherwise standard manufacture is hereinafter described in detail and illustrated in the accompanying drawings, in which—

Fig. 1 is a view in front elevation of the main part of a cutting machine with the indicating device applied thereto. 85

Fig. 2 is an enlarged view in end elevation of the machine.

Fig. 3 is an enlarged detail view in cross section of the pointer, and oscillating rod, taken on line 3, 3 of Fig. 1, and 90

Fig. 4 is an enlarged detail view in section, taken on line 4, 4 of Fig. 1, showing the actuating mechanism of the indicating device.

Referring in a more general way to the 95 paper cutting machine which may be said to be typical of machines of this character, the same comprises a frame consisting of vertical side frame members 1, 1 spaced apart, and supporting at their upper ends 100 a comparatively large feed roll 2 journalled in bearings 3, 3 mounted on said frame members, and driven by means of a belt pulley 4 mounted on the shaft 2^a of the feed roll, and a belt 5 leading to a source of 105 power. Immediately above the main feed roll 2 is a smaller guide roll 6 mounted in vertical journal hangers 7, 7 carried on top

of the frame members 1, 1. Below the main feed roll 2 and somewhat forwardly thereof is the rotary cutter 8 comprising a shaft 9 journalled in bearings 10, 10 preferably adjustable vertically upon the machine frame, by means of hand wheels 11, 11 and connecting screw shafts 12, 12. Mounted at the ends of the cutter shaft 9 are disks 13, 13 to which are fixed the ends of the cutting blade 14, which is also secured to the shaft intermediate its ends, by means of collars 15, mounted on the shaft 9 and fixed to said blade. One end of the cutter shaft 9 extends beyond one of the (right hand) frame members 1 and has mounted thereon a gear wheel 16 forming one element of the cutter driving mechanism, which includes also a well known type of speed regulating mechanism, namely, cone pulleys and shiftable belt connecting the two pulleys, one of said pulleys 17 being shown (Fig. 1.) The cone pulley 17 is mounted upon a shaft 18, which carries a pinion 19 meshing with the gear wheel 16 of the cutter. This type of speed regulation being a common one, it does not require disclosure in detail, and it is thought sufficient to point out that the speed of the pulley is regulated by shifting the belt connecting it with another like pulley driven at a constant speed. The shifting of the belt, and hence the speed of the pulley 17, as well as that of the cutter, is controlled by the operator by means of a hand wheel 20, located within easy reach of the operator standing in front of the machine, and in a position to observe the performance of the machine and the results of the adjustments made in the speed regulating mechanism.

On the opposite (left) side of the machine is provided a train of intermeshing gear wheels 21 connecting the cutter shaft 9 with a large vertical hand wheel 22, said gear wheels being mounted on stub shafts mounted on the side of the frame member 1 and on the shafts 9, and a shaft 23, carrying the hand wheel 22, the latter being equipped with a pawl and ratchet mechanism 24 for convenience in manipulation. The hand wheel is used for adjusting the machine to the different lengths indicated that the sheet is to be cut.

The paper is preferably fed to the cutting machine in the form of continuous webs 25 of desired width, these webs, shown as 55 three in number, passing over the main feed roll 2 and vertically downward into the path of the rotary cutter 8 which is rotated in the same direction as the paper travels, that is, in a counter-clockwise direction. In the paper are formed water-marks 26 or other visible marks of identification, preferably located intermediate the side margins thereof and reoccur at predetermined intervals throughout the web, these 65 intervals being ordinarily gauged by the

size of the sheets into which the paper is to be ultimately cut. For example, if a web is to be made up into sheets having dimensions of 11 inches in length and 8 $\frac{1}{2}$ inches in width, the width of the web would 70 be 17 inches and the water-marks would be arranged in pairs each spaced 4 $\frac{1}{2}$ inches from the side margins of the web, and each pair spaced apart 11 inches longitudinally of the web. Thus the web in passing through 75 the cutting machine would first be cut into sheets of 17 inches by 22 inches in size, which in turn could be cut into four sheets with a water-mark centrally located in each sheet. 80

As hereinbefore suggested, it is desirable that the water-mark be uniformly positioned in the sheets, and in the absence of indicating means whereby the operator may regulate the performance of the machine, it is 85 difficult to compensate for the creeping action of the webs heretofore referred to.

Such an indicating means is herein disclosed as comprising parts as follows: Extending immediately in front of and parallel to the main feed roll is an oscillating rod or shaft 27, journalled in bearings 28, 28 mounted upon the side frame members 1, 1. Slidably mounted on the rock shaft is a collar 29 adapted to be slidably adjustable along the shaft and to be fixed in any position by means of a set screw 29^a. A pointer or finger 30 is mounted in the collar the same extending transversely to the shaft, and in a general downward direction, and preferably having the form of a flexible pointed blade. The rod is adjustable endwise within a slot formed in the collar 29, and is held in adjusted position by means of a thumb screw 30^a. 105

Pivotedly secured above the rotary cutter and in vertical alinement with one of the discs 13 at the end (left) of said cutter, is a lever 31 depending vertically from a supporting arm 32 integral with the adjacent oscillating rod bearing 28, and having a forked end in which the upper end of the lever is swung. The lower end of the lever terminates adjacent to the periphery of the cutter disc 13, and in the path of a lug 33 secured to the disc at a predetermined position with relation to the cutter bar 14, hereinafter to be disclosed. Connected with the lever 31 at a point substantially midway between its ends is a flexible cord 34 110 (Fig. 4) which passes over the upper surface of the rod and is fastened to the opposite or rear side thereof at 35. Fastened at the same point 35 and passing beneath the rod 27 is a comparatively long cord 36 120 extending in a forward and downwardly direction and secured at its free end to an extensible rod 37 secured at its outer end to a horizontal frame member 38 of the machine, said extensible rod being provided 125 130

intermediate its ends with a turn-buckle 37^a for regulating the tension in the parts of the actuating mechanism.

The longer cord is preferably of a fibrous substance such as hemp, or other material which when woven in cord-like form has a certain amount of residual elasticity, that is to say, when tension is applied to the cord, and then suddenly released, there is sufficient elasticity to effect a sudden and sharp reaction. This property is well known to exist in all fibrous cords and rope, if not in all flexible cables, although they are not ordinarily considered as being elastic. Connected with the lever 31 is a coil spring 40 or other elongated elastic member, extending substantially parallel with the cord 36, and also connected at its free end with the end of the extensible rod 37. The parts of the indicating mechanism are preferably associated so that the lever 31 depends vertically when out of contact with the lug, and in such position of the lever the cords 34 and 36 are taut (though not stretched to any degree) and the spring is contracted. Furthermore, the collar is so positioned on the shaft and the pointer 30 stands vertically and away from the surface of the web 25.

In describing the operation of the web, it will be assumed that the webs 25 are passed between the feed rolls, and the cutter and feed mechanism accurately adjusted so that the water-marks of each web are positioned midway between the imaginary transverse lines along which the webs will be cut. Having thus positioned the webs, the pointer is then adjusted transversely so as to register with an imaginary line defining certain points; as for instance, the centers of the water-marks of one of the webs. Therefore it is necessary to adjust the indicating device so that it will be actuated at the instant the cutting operation occurs, that is, the indicating or pointing synchronized with the cutting so that the pointer is moved quickly toward and from the surface of the web as each cut is made. Manifestly, if the pointer coincides with the centers of each water-mark, the proper location of said water-marks is secured. On the other hand, if the pointer points ahead or behind the water-marks, it is an indication that the water-marks are not properly located on the cut sheets, and adjustment of the speed of the cutter is required. It is obvious that, having adjusted one web, the remaining webs would be adjusted to correspond.

Now, if the machine is started, it is reasonable to assume that the first cuts will be along the predetermined line, but it is not to be assumed that the cutting will continue so, for the reasons hereinbefore set forth. Manifestly, an initial setting is necessary, which would be effected by oper-

ating the machine by hand until the proper synchronism was obtained, that is to say, when the conditions are such that the indicator will be actuated at the instant each cutting operation occurs, or, once during each revolution of the cutter. The operation of the indicator originates in the contact between the lug 33 and the lower end of the lever 31, the former having preferably a gradually tapering cam surface terminating in an abrupt shoulder 33^a, indicating the point where contact is broken between the lug and the lever, it being observed that said shoulder is in alinement with the cutter blade. Now, assuming the cutter is rotating in a counter-clockwise direction, it is manifest that as the lug comes into contact with the end of the lever the latter is forced inwardly as it rides upon the surface of the lug, this displacement of the arm being accompanied by a slackening of the cord 34 connecting the lever to the shaft and an expansion of the spring 40. The longer cord 36 is preferably so adjusted that it remains taut during this period of actuation of the indicating mechanism. Thus the oscillating rod undergoes no movement inasmuch as there is no tension on either cord. However, at the instant the lever is released by the lug, the spring contracts, throwing the lever forward with a sudden movement which is transmitted to the rod, through the now tightened connecting cord 34, thereby effecting an equally sudden oscillating of the rod and of the pointer toward the web surface and to the predetermined point of the water-mark. The rocking of the shaft in the direction to actuate the pointer toward the web is opposed by the lower cord 36 inasmuch as the oscillation of the rod in a clockwise direction tends to stretch or lengthen the same. Thus when the shaft has been rotated to the indicating position of the pointer, the cord 36 will have reached the limit of its so-called residual elasticity, and the reaction will be instantaneous, causing the rod to be suddenly rotated in the opposite direction or sharply thrown outwardly from the surface of the web to its original position.

Inasmuch as the web is fed through the machine at a high velocity and the cutter is rotated at a correspondingly high velocity it is at once apparent that the movement of the pointer must be instantaneous and sharp not only in the pointing movement but in returning therefrom, for it must be borne in mind that the water-marks pass with great speed before the eyes of the operator, and hence the indicating action must be sharply defined in order that the pointer may effectively indicate the position of the water-mark with reference to the sheets. It is for this reason that non-elastic cords (as distinguished from inherently elastic springs

or the like) are utilized for providing the forces for actually moving the pointer, it being obvious that reaction of elastic members is not sufficiently rapid to afford the sharp movement that is necessary.

By the particular arrangement of parts and the novel employment of the properties thereof, a means has been devised which will enable the cutting of the paper to be 10 accomplished with due regard for the location of the water-marks on the separate sheets, and more especially a device which affords the operator of the machine a constant indication as to whether or not the 15 water-marks are creeping ahead or behind their proper position in the sheets, thus enabling him in making the necessary adjustments in the speed of the cutter to overcome any discrepancy in the cutting operation.

20 Although I have shown and described a preferred embodiment of the invention, it is to be understood that the details of construction may be variously modified without departing from the spirit of the invention. Therefore, I do not wish to be limited 25 in the scope of the invention except in so far as expressly set forth in the appended claims.

I claim as my invention:

30 1. In an apparatus of the class described, the combination of means for feeding a web of paper forwardly at high velocity, a cutter adapted successively to cut lengths from said web forming sheets, an indicator operatively connected with the cutter and adapted successively to sharply indicate a fixed 35 easily visible point in the plane of the web at a predetermined point in the cutter cycle, and means for regulating the speed of operation of the cutter whereby by maintaining an approximately fixed relationship between a visible recurring mark in the traveling web and the point successively sharply indicated by the indicator the mark may be 40 properly located in the cut sheets.

45 2. In an apparatus of the class described, the combination of a cutter adapted to cut successive lengths from a traveling web of paper, means for varying the rapidity of the cutting strokes, a movable indicator adapted to point to the web at a predetermined point in the operation of the cutter, whereby the rapidity of cutter strokes may be adjusted to maintain an approximately 50 fixed relation between the indicator when pointing, and a successively appearing visible mark in the web so as to prevent a water-mark or the like from creeping out of proper position in the cut sheets.

60 3. In an apparatus of the class described, the combination of means for feeding a web of paper forwardly at high velocity, a cutter adapted successively to cut lengths from said web, thereby forming sheets of paper, 65 an indicator operatively connected with the

cutter and adapted to direct attention by a sudden recurring movement to a predetermined point in the plane of the web, said movement occurring in predetermined time relationship with the cutting of the web, 70 and means for varying the relative speeds of the web feeding means and cutter, whereby by maintaining such speed relationship so as to cause a recurring visible mark in the web to be positioned in predetermined 75 relationship with the point to which attention is directed by the indicator by the sudden movements of the latter whereby said visible mark may be properly positioned in the cut sheets.

4. In an apparatus of the class described, the combination of means for feeding a web of paper forwardly, means for cutting said paper as it is fed forwardly, into sheets, a pointer positioned adjacent said traveling web and operatively connected with the cutter and adapted by a distinct pointing movement successively to indicate a predetermined spot on the surface of the web, in predetermined time relationship with the successive cutting operations of the cutter, and means for changing the length of the sheets whereby said last named means may be operated to maintain an approximately fixed relationship between said spot in the web indicated by the pointer and a recurring visible mark in the paper.

5. In an apparatus of the class described, the combination of means for feeding a web of paper forwardly, means for cutting said paper as it is fed forwardly into sheets, a pointer positioned above said traveling web and operatively connected with the cutter, and adapted by a distinct pointing movement successively to indicate a predetermined spot in the surface along which the web travels in predetermined time relationship with the successive cutting operations of the cutter, and means for changing the length of the sheets whereby said last named means may be operated to maintain an approximately fixed relationship between the spot in the plane of the web indicated by the pointer and a recurring visible mark in the paper, and means whereby said predetermined spot in the surface along which the web travels may be located as desired.

6. In a paper cutting machine, the combination of means for feeding a web of paper forwardly, a rotary cutter located at the delivery end of the machine and adapted to cut the web into sheets as delivered by the machine, a pointer mounted above the traveling web, and connections from the rotary cutter for sharply oscillating said pointer to effect the momentary indication of a predetermined point in the plane of the web, at a predetermined point in the cutter cycle.

7. In a paper cutting machine, the combination of means for feeding a web of paper

forwardly, a rotary cutter located at the delivery end of the machine and adapted to cut the web into sheets as delivered by the machine, an oscillatory rod mounted adjacent to said web, a pointer carried by said rod and connections from the rotary cutter to said rod to oscillate the same and cause a pointing movement of the pointer in definite time relationship with the cutting operations of the cutter.

8. In an apparatus of the class described, the combination of means for feeding a web of paper forwardly, a cutter adapted to cut the same into sheets during the travel of the web, a pointer poised above the web, means for causing said pointer to make a sudden pointing movement and recovery, all so constructed and arranged that the pointing movement bears a predetermined time relationship with the successive cutting operations of the cutter.

9. In an apparatus of the class described, the combination of means for feeding a web of paper forwardly, a cutter adapted to cut the same into sheets during the travel of the web, an oscillatory member mounted above the web, a pointer mounted thereon, means for causing a sudden oscillation of said member to cause the pointer to make a

sudden pointing movement, said means being so operatively connected with the cutter so as to maintain a definite time relationship between the pointing movement and the cutting action.

10. An apparatus of the class described, and in combination, means for feeding a web of paper forwardly, a cutter adapted to cut the same into sheets during the travel of the web, an oscillatory support arranged transversely of the web, a pointer mounted on said support, means mechanically connected with the cutter and operated thereby to oscillate said support and cause pointing movement of the pointer.

11. An apparatus of the class described, and in combination, means for feeding a web of paper forwardly, a cutter adapted to cut the same into sheets during the travel of the web, a pointer poised above the web, and operative connections from the cutter to the pointer, whereby the pointer is controlled by the cutter independently of the web.

In witness whereof, I hereunto subscribe my name this 2nd day of August, A. D., 1920.

FRANK O. SCOTT.
